(57) **CLAIM**

The ornamental design for an exercise mat as shown and described.

DESCRIPTION

FIG. 1 is a top perspective view of an exercise mat showing our new design.

FIG. 2 is a bottom perspective view thereof.

FIG. 3 is a top view thereof.

FIG. 4 is a bottom view thereof; and,

FIG. 5 is a left side view thereof. A right side, front, and rear view being the same.

The broken lines show portions of the article that form no part of the claimed design.
